PITCHER OR SIMILAR ARTICLE

Frank J. Benes, Lancaster, Ohio, assignor to Anchor Hocking Glass Corporation, Lancaster, Ohio, a corporation of Delaware

Original design application May 26, 1967, Ser. No. 7,274, now Patent No. 211,037, dated May 14, 1968. Divided and this application Dec. 14, 1967, Ser. No. 9,771

Term of patent 14 years

Int. Cl. D7—01

U.S. Cl. D36—2

FIG. 1.

FIG. 2.

FIG. 1 is an elevational view of a pitcher or similar article showing my new design; and

FIG. 2 is a top view thereof.

The present application is a division of co-pending U.S. design patent application Ser. No. 7,274 filed May 26, 1967 and now Patent No. 211,037.

I claim:

The ornamental design for a pitcher or similar article, substantially as shown and described.
